UNITED STATES PATENT OFFICE.

THOMAS W. SCOTT, OF BALTIMORE, MARYLAND, ASSIGNOR TO THE AMERICAN TRAIN CONTROL COMPANY, OF BALTIMORE, MARYLAND, A CORPORATION OF MARYLAND.

TRAIN-CONTROL APPARATUS.

1,361,410.

Specification of Letters Patent.

Patented Dec. 7, 1920.

Application filed March 15, 1917, Serial No. 154,992. Renewed June 26, 1920. Serial No. 392,043.

To all whom it may concern:

Be it known that I, THOMAS W. SCOTT, a citizen of the United States, residing at Baltimore city, in the State of Maryland, have 5 invented certain new and useful Improvements in Train-Control Apparatus, of which the following is a specification.

This invention relates to improvements in train control apparatus and more particularly has to do with an improved arrangement of circuits for effecting an operation of the cab signals and the automatic stop device,—the two devices being arranged to operate in conjunction with and through the 15 operation of one or another of two contact shoes when either of the latter engage a ramp rail.

My present invention is designed to utilize a single ramp rail in a block to effect an operation of both the signal and stop mechanisms and provides an improved arrangement of devices and circuits whereby the stop valve devices are controlled by the signal control devices so that the signal and 25 stop mechanisms are inseparably related.

I also provide two contact shoes on the vehicle,—one at each side thereof and I mechanically connect each shoe with a switch device so that the circuits controlling both 30 the signal and stop devices will be opened or closed, as the case may be, when either of said shoes and the switch or switches operated thereby are actuated.

The invention is illustrated in the accompanying drawing wherein the devices and circuits are shown diagrammatically in a single view.

Referring to the drawing the numeral 1, designates a signal control relay; 2, the stop-valve magnet; 3, 4 and 5, the green yellow and red light-signals; 6 and 7 the two contact shoes and 8, the vehicle current supply or battery. All of these parts are carried on the vehicle together with certain wire 45 connections for maintaining them through electric circuits which will presently be explained.

In rail road operations it is not always possible to locate all the ramp rails, which 50 are utilized to actuate the contact shoes, on the same side of the track-way. In fact, it frequently happens that it is desirable to locate a ramp at a particular place but conditions on the one side of the track are such 55 as to make it impractical to place the ramp

there, but the same can be placed directly opposite. On account of such conditions I have found, in actual practice, that it is much better to provide two contact shoes on the vehicle,—one at each side thereof so that 60 the ramp rails may be located on either side of the track as desired. I also provide two shoe switches 9 and 10, respectively for the shoe 6, and two shoe switches 11 and 12, for the shoe 7.

These shoe-switches are mechanically connected to the shoes and two of them are operated at a time upon the movement of a shoe during its travel onto and from a ramp rail,—it being understood, however, that at 70 no time, in the operation of my invention, will both shoes be actuated simultaneously.

The signal control relay 1, is provided with three armatures which are designated 13, 14 and 15, respectively and armature 13, 75 is included in a stick circuit that is normally maintained while the vehicle is traveling between ramp rails from the vehicle current supply through shoe switches 12 and 10 to the control relay and back to said current 80 supply, thereby keeping the control magnet energized. This normal circuit is as follows: from current supply by wires 16—17—18 and 19 to armature 13; then by wire 20, to and through shoe switch 12; then by wire 21, 85 to and through shoe switch 10, and by wires 22 and 23 to and through control relay 1, and return by wires 24, 25, 26 and 27 to negative side of current supply.

It will thus be seen that this normal circuit includes both shoe switches 12 and 10, when the latter are closed, but will be interrupted when either shoe passes onto a ramp rail and opens either of said switches 12 or 10. The interruption, however of this 95 normal circuit by the opening of the switches, does not necessarily mean a de-energization of control relay 1, because, when either shoe 6 or 7, passes onto and over an energized ramp rail, current will be 100 picked up from such energized ramp and be conveyed from such shoe by wires 28 and 29, it depending upon which shoe is operated, to wire 30, and from the latter wire to wire 23, to control relay 1, and return by 105 wires 24, 25, 26 and 31 to the axle 32; wheel 33 and track rail 34, back to its source, which is external to the vehicle as will presently be explained. It will thus be seen that as long as the indicator relay 1, is en- 110

ergized either by the normal vehicle current or by current picked up from a ramp, armature 15, will be held up into engagement with contact point 35, so that current 5 from the vehicle current-supply 8, may pass by wires 16, 17, 18, 36 to and through armature 15; then pass by wire 38, to and through the green lamp or clear signal 3; then return by wires 39, 40, 25, 26, and 27, back to 10 the vehicle current supply 8, thus giving a green or clear indication as long as control relay 1, is energized, because as long as armature 15, is held up it acts as a closed switch in a circuit from the vehicle current- 15 supply through the green or clear indicator 3, no matter whether control relay, 1, is being energized by the vehicle current supply, or by current picked up from an energized ramp.

20 Valve magnet 2, controls two armatures 41 and 42, in addition to its usual function of venting the air brake train-line to apply the brakes, or to effect such other operation as will result in stopping the vehicle. This 25 magnet is also normally controlled by a stick circuit which includes the armature 41, shoe switches 11, and 9, magnet 2, and vehicle current supply 8—the circuit being as follows: from current supply 8, by 30 wire 43; armature 41; wire 44, to and through shoe switch 11; then by wire 45, to and through shoe switch 9; wires 46, 47 and 48 to and through magnet 2, and return by wires 49, 26 and 27, to vehicle current 35 supply 8. The circuit just described is the normal circuit for maintaining said valve magnet, and is maintained as long as shoe- switches 11 and 9, are both closed, and control magnet 1, is energized by current from 40 the vehicle current-supply 8. There are times however when one or the other of the shoe-switches 11 or 9, is opened by the shoe 45 7, or 6, riding up onto a ramp rail, and at such times the normal circuit through the 50 valve magnet 2, will be interrupted. If, however, the ramp-rail that is engaged by one of the contact shoes is energized, the opening of the switch of that contact shoe will not effect a deenergization of valve 55 magnet 2, because control magnet 1, will be kept energized by the current picked up from the energized ramp, and as long as said control magnet is energized, another circuit that is independent of the shoe switches, 11 or 9, will be maintained through armature 14 and the valve magnet from the vehicle current supply to keep the valve magnet energized, as follows:

From vehicle current-supply 8, by wires 60 16, 17, 18, 36, 50, to and through armature 14, of the control relay; then by wires 51, 47 and 48, to and through valve magnet 2, and return by wires 49, 26 and 27 to vehicle current-supply. Thus it will be seen 65 that as long as control magnet 1, is ener-

gized, either by the normal vehicle circuit or by current picked up from an energized ramp rail, the valve magnet 2, will be kept energized by current from the vehicle current supply, so that a clear signal through 70 lamp 3, will be maintained.

The ramp rail 52, has a connection 53, to a contact point 54, with which latter an armature 55, of a trackway relay 56, engages, and a wire 57, connects the heel of said armature with one side of track-way current-supply 58. The other side of this current supply 58, is connected by a wire 59, with the track-rail 34, so that current picked up from a ramp will be conveyed by wires 28 or 29, to wire 30, and 23 to control magnet 1, and be returned by wires 24, 25, 26 and 31 to the axle, wheel and track rail and then by wire 59 to track-way current supply 58, which supplies the ramp rail with current.

When a deenergized ramp rail is engaged by either shoe, and the switches of that shoe are opened, both the control relay 1 and the valve magnet 2, will be simultaneously 90 deenergized; the application of the brakes, or other control mechanism, will result through the operations of the deenergized valve magnet 2, and simultaneously therewith a danger signal at 5, will be displayed. 95 This danger signal is operated by current from the vehicle current supply 8, by a circuit which is established through armature 15, of control relay 1, in the down position, and through armature 42, of the valve magnet 2, which will also be in the down position, 100 as follows:

From current supply 8, by wires 16, 17, 18, 36, 37 to armature 15, then through said armature, which will be down to wire 60, 105 and armature 42, of valve magnet 2, which latter armature will also be down; then through said armature 42, to wire 61 and danger or red signal 5, and return by wires 62, 67, 40, 25, 26, and 27, to the said vehicle 110 current supply 8. Thus it will be seen that when relay 1 and valve magnet 2, are both deenergized, the danger signal will be displayed at 5, and the stop mechanism controlled by magnet 2, will be actuated to 115 bring the vehicle to a stop.

After an automatic stop has been effected because of the deenergization of both control relay 1 and stop valve magnet 2, the vehicle cannot proceed until at least the stop 120 valve magnet has again been energized, and then only under a caution signal 4.

To enable this to be done I provide a switch device which I prefer to locate on the vehicle, at a place that is inaccessible 125 from the cab, so the engineer must get off the vehicle to reach it, thus insuring the complete stopping of the vehicle or train.

In the diagrammatic illustrations in the drawing, this reset switch is designated 63, 130

and has one side connected by a wire 64, with wire 17, while its other side is connected to wire 48, so that the circuit of the valve magnet 2, from the vehicle current supply is as follows:

From vehicle current-supply 8, by wires 16, 17 and 64, to and across reset switch 63; then by wire 48, to and through valve magnet 2; then return by wires 49, 26 and 27 10 back to current supply 8, thus energizing magnet 2, and lifting armatures 41 and 42. Armature 42, when lifted, will engage a contact on a wire 65, which latter leads to the caution signal or yellow lamp 4, while a 15 wire 60, from said armature leads to a contact which is engaged by armature 15, of the control relay 1, because this relay, under the conditions now described will be deenergized. It will thus be seen that when 20 control relay 1, is deenergized and valve magnet 2, is energized by an operation of the reset switch through a stick circuit, the caution signal 4, will be operated by a circuit from vehicle current supply 8, by wires 25 16, 17, 18, 36, and 37, through armature 15, on the down position; then through wire 60 to and through armature 42, which will be up; then by wire 65, to caution or yellow lamp 4, and by wires 66, 67, 40, 25, 26, and 30 27, back to the vehicle current supply 8. Under these conditions the vehicle can proceed with the caution signal until an energized ramp rail is reached, whereupon the current picked up from such energized ramp 35 will again energize control relay 1; cut-off the caution signal and reestablish the clear or green signal 3, and the vehicle can then proceed under clear conditions.

From the foregoing explanations it is to be 40 understood that my invention contemplates employing but one ramp rail to a block, and to utilize two contact shoes; a control relay; a valve relay; a current supply on the vehicle and clear, caution and danger signals also 45 on the vehicle, with circuits and connections, so that the operation of either shoe by a deenergized ramp rail will simultaneously deenergize both the control and valve relays,

thereby producing a stop and giving a danger signal; to also provide for manually effecting an energization of the valve relay to permit the vehicle to proceed under a caution signal and to further provide for automatically changing from a caution to a clear signal through the energization of the 55 control relay if the next ramp engaged by a contact shoe is energized.

Having described my invention what I claim and desire to secure by United States Letters Patent is,—

1. In a combined control and signal mechanism for vehicles the combination with a vehicle having a current supply, of two contact shoes on the vehicle; shoe switches operated by each shoe; a control 60 relay on the vehicle; a valve relay also on the vehicle; a stick circuit including one switch of both shoes for normally maintaining the control relay; a stick circuit including another switch of both shoes for normally maintaining the valve relay and means whereby when either shoe engages a deenergized ramp both relays will be simultaneously deenergized.

2. In a combined control and signal mechanism for vehicles the combination with a vehicle having a current supply, of two contact shoes on the vehicle; a plurality of shoe switches operated by each shoe; a signal control relay on the vehicle; a stop valve 65 relay also on the vehicle; stick circuits for normally maintaining said relays, connections between the contact shoes and the control relay to maintain the latter by current picked up from a ramp rail, and connections 70 between the vehicle current supply, an armature of the control relay and the valve relay for maintaining the valve relay by the vehicle current while the control relay is energized.

In testimony whereof I affix my signature in the presence of two witnesses.

THOMAS W. SCOTT.
